UNITED STATES PATENT OFFICE.

SAMUEL A. BENNER, OF PITTSBURGH, PENNSYLVANIA.

TRUCK SIDE PEDESTAL.

1,271,120.

Specification of Letters Patent.

Patented July 2, 1918.

Application filed September 22, 1913, Serial No. 791,051. Renewed November 23, 1917. Serial No. 203,623.

To all whom it may concern:

Be it known that I, SAMUEL A. BENNER, a citizen of the United States, and resident of Pittsburgh, in the county of Allegheny and State of Pennsylvania, have invented a new and useful Improvement in Truck Side Pedestals; and I do hereby declare the following to be a full, clear, and exact description thereof.

10 My invention relates to improvements in car construction and is particularly concerned with improvements in the construction and manner of assembling the truck side pedestal with the side frame of the truck. The invention has for its object the provision of a pedestal of unusually strong and at the same time light construction which may be formed of a rolled section properly cut or sawed and formed up into pedestal shape and which may be most effectively assembled with and secured to the truck side frame.

15 A further object is to provide in the pedestal member a spring plank base of adequate width to support the usual group of bolster springs, said base having laterally reinforcing members extending to either side of the tension member of the truck side frame to afford a powerful support for the springs in the case of trucks for use with exceptionally heavy cars. A further object is to provide a pedestal of very simple and strong construction which may be turned out at minimum cost.

20 The invention herein described comprehends not only the construction for accomplishing the above objects broadly, but also specifically a construction in which the pedestal is formed of a rolled blank, the web of which is cut or sawed longitudinally and transversely of its width in a plane parallel with the flat faces of said blank.

25 In the drawings which illustrate a preferred embodiment of the invention, Figure 1 is a side elevation of a truck side frame and pedestal embodying the invention; Fig. 2 is a longitudinal vertical section of the same; Fig. 3 is an underside view of the tension member of the side frame, showing the manner of attaching the pedestal thereto; Fig. 4 is a transverse section on the line 4—4, Fig. 1; Fig. 5 is a view of a rolled section or blank from which the pedestal may be constructed; Fig. 6 is an edge view of the blank; and Fig. 7 is a plan view of the blank shown in Fig. 6 illustrating the man-

ner of shearing the same before bending it to pedestal shape.

Referring to Figs. 1, 2 and 4, the side frame 1 may be formed from a blank having the web 2 which is sawed or cut longitudinally across its width between the points *a* and *b* and expanded into the form shown, the resulting compression member therefore consists of a channeled member comprising the web 3 and flanges 4, 4, while the tension member consists of a channeled portion having the web 5 and the flanges 6, 6. (See Fig. 4). The journal boxes 7 are secured in place beneath the unsevered portions 2 of the web of the blank by means of the bolts 8.

The truck pedestal in which the invention mainly consists is formed from a blank shown in perspective view in Fig. 5 and in edge and plan views respectively in Figs. 6 and 7. This blank comprises the web 9 having flanges or wings 10, 10 at their faces, and the flanges 11 at the opposite face. The web of the blank is cut or sawed along the line 12 transversely of its width and in a plane parallel with the opposite flat faces thereof. This cut or sawed kerf terminates at 13 within the end of the web. The uncut end of the rib is notched or recessed as 14 Fig. 7 leaving the opposite wing portions 15—15. The wings or flanges 10 and 11 are each sheared along lines *c*, *d*, Fig. 6, and then are bent back forming lateral wings 16, and 17, Fig. 7. The portions of the web upon the outside of the flanges or wings 10, 11 are sheared along the lines 20, 20, and 21, 21, Fig. 7, to form the reduced upper portion 22, Fig. 4, of the pedestal. The two parts 18 and 19 of the web on each side of the cut 12 are then bent or spread at right angles to the uncut portion 9, Fig. 6, or wings 15, Fig. 7, and are shaped up into the form shown in Figs. 1 and 2 in which the half plates 18 and 19 form the web or inner wall of the pedestal and the wings 10 and 11 form reinforcing flanges extending entirely around the outer side of the pedestal. When the parts of the web are spread as described, the wings 16 and 17 assume the position shown in Figs. 1 to 4 relatively to the wings 15 formed by the uncut portions of the extremity of the web, and the unsheared portions of the web within the lines 20, 20, form reinforcing strengthening wings 23, 23 for the base or spring bearing portion 24 of the pedestal. It will thus be

seen that the spring or base blank 24 is re-inforced or strengthened laterally not only by the wings 23, 23 above, but also by the transverse web which extends across beneath the center of the pedestal and is formed by the wings 15 of the web and the wings 16 and 17 of the flanges 10 and 11, respectively. These parts may be riveted together as at 25. When the pedestal is assembled with 10 the side frame, the compression member of the latter passes between the flanges 10 and 11 and the tension member also passes between the same flanges and through the recess 14 of the uncut end of the web, and said flanges 16 10 and 11 are riveted to the flanges 4 and 6, respectively, of the compression and tension members as at 26 and 27.

Thus it will be seen that by shaping up the pedestal from a section such as that shown in Fig. 5 having its web or cut transversely, I provide not only a strong form of pedestal frame, but also provide reinforcing webs for the spring base plank extending laterally upon opposite sides of the tension 20 member. These webs together with the laterally extending wings 23, 23, Fig. 4 afford powerful reinforcements of the spring base plank for the support of the bolster springs.

What I claim is:

30 1. In car truck construction, the combination with the compression and tension members of the side frame, of a pedestal formed of a rolled section having its web split transversely in a plane parallel with its opposite flat faces, said split sections being formed up in the shape of a pedestal frame with one extremity of the web forming laterally reinforcing webs extending laterally to each side of the tension member beneath the spring 35 plank base of the pedestal.

40 2. In car truck construction, the combination with the compression and tension members of the side frame, of a pedestal formed of a rolled section having a web, said web being split transversely from one end at a point adjacent the opposite end in a plane parallel to the flat faces of the web, said split sections being shaped up to form the spring plank base side wall and top walls 45 of the pedestal and said unsplit portion forming reinforcing webs beneath the spring plank base portion extending laterally to each side of the tension member.

50 3. In car truck construction, the combination with the compression and tension members of the side frame, of a pedestal formed of a rolled section comprising a web, and pairs of wings or flanges extending from each side thereof, respectively, said web being split longitudinally transversely of its width in a plane parallel with the opposite flat faces, said split portions being shaped to form the spring plank base, side walls and top walls of the pedestal, said flanges forming reinforcing members extending

completely around the outside wall of the pedestal, one end portion of said web and adjacent end portions of said flanges being constructed and arranged to form reinforcing wings or webs extending laterally at 70 either side of the tension member beneath the spring supporting base of the pedestal.

4. In car truck construction, the combination with the compression and tension members of the side frame, of a pedestal formed of a rolled section comprising a web, and pairs of wings or flanges extending from each side thereof respectively, said web being split longitudinally transversely of its width in a plane parallel with the opposite 80 flat faces, said split portions being shaped to form the spring plank base, side walls and top walls of the pedestal, said flanges forming reinforcing members extending completely around the outside wall of the 85 pedestal, one end portion of said web and the adjacent end portions of said flanges being constructed and arranged to form reinforcing wings or webs extending laterally to either side of the tension member beneath the spring supporting base of the pedestal, the split portions of the web of the blank 90 at the upper part of the pedestal being sheared away to form guideways of reduced width for the guidance of the bolster end. 95

5. In car truck construction, the combination with the compression and tension members of the side frame, of a pedestal formed of a rolled section comprising a web and flanges extending from the opposite faces intermediate of the side edges thereof, said web being split longitudinally and transversely of its width in a plane substantially parallel with its opposite flat faces from one end to a point adjacent the opposite end, 105 the split portions of said web being spread apart and shaped to form the base side walls and top of the pedestal with said flanges forming reinforcing members extending completely around the outside of the pedestal, the unsplit portion of said web being recessed to fit over the tension member and the remaining parts of said unsplit portion forming reinforcing wings extending laterally from each side of the tension member 110 beneath the base of the pedestal.

6. In car truck construction, the combination with the compression and tension members of the side frame, of a pedestal formed of a rolled section comprising a web and 120 flanges extending from the opposite faces intermediate of the side edges thereof, said web being split longitudinally and transversely of its width in a plane substantially parallel with its opposite flat faces from one 125 end to a point adjacent the opposite end, the split portions of said web being spread apart and shaped to form the base side walls and top of the pedestal with said flanges forming reinforcing members extending 130

- completely around the outside of the pedestal, the unsplit portion of said web being recesses to fit over the tension member, and the remaining parts of said unsplit portion 5 forming reinforcing wings extending laterally from each side of the tension member beneath the base of the pedestal, and the ends of said flanges of the rolled section adjacent said recess being sheared from the 10 flat faces of the web and bent laterally to reinforce the said reinforcing wings of the pedestal base.
7. In car truck construction the combination with a truck side frame having a compression member consisting of an upwardly 15 opening continuous channel portion, and a tension member consisting of a downwardly opening continuous channel portion, of a pedestal having reinforcing webs extending 20 laterally beneath its spring plank base, the flanges of the pedestal section extending along each side of the side walls of the compression and tension members, respectively, and being secured thereto.
8. In car truck construction, the combination with a truck side frame having a compression member consisting of an upwardly 25 opening continuous channel, and a tension member consisting of a downwardly opening continuous channel portion, of a pedestal formed of a rolled section having its web 30 split transversely in a plane parallel with its opposite flat faces, said split sections being formed up in the shape of a pedestal
- frame with one extremity of the web forming laterally reinforcing webs extending laterally to each side of the tension member beneath the spring base of the pedestal, the flanges of the pedestal section extending along each side of the side walls of the compression and tension members, respectively, and being secured thereto. 35
9. In car truck construction, the combination with a truck side frame having a compression member consisting of an upwardly 40 opening continuous channel portion and a tension member consisting of a downwardly opening continuous channel portion, of a pedestal formed of a rolled section having a web, said web being split transversely from 45 one end to a point adjacent the opposite end in a plane parallel to the flat faces of the web, said split sections being shaped to form the spring plank base side wall and top walls of the pedestal and said unsplit 50 portion forming reinforcing webs beneath the spring plank base portion extending laterally to each side of the tension member, the flanges of the pedestal section extending along each side of the side walls of 55 the compression and tension members, respectively, and being secured thereto. 60

In testimony whereof, I the said SAMUEL A. BENNER have hereunto set my hand.

SAMUEL A. BENNER.
